UNITED STATES PATENT OFFICE.

STEVE SIFTER, OF CLAY CENTER, OHIO.

PLOW.

1,165,808.

Specification of Letters Patent. Patented Dec. 28, 1915.

Application filed October 6, 1913. Serial No. 793,593.

To all whom it may concern:

Be it known that I, STEVE SIFTER, a citizen of Hungary, residing at Clay Center, in the county of Ottawa and State of Ohio, 5 have invented certain new and useful Improvements in Plows, of which the following is a specification.

This invention relates to improvements in plows and its object is to produce a plow 10 with a novel form of mold board of maximum efficiency and the combination therewith of an adjustable colter and of novel adjusting means therefor.

With the foregoing and other objects in 15 view the invention consists in the combination and arrangement of parts to be herein-after fully described in the following specification, pointed out in the claim and illustrated in the accompanying drawings which 20 form a part of said specification and in which—

Figure 1 is a side elevation of my improved plow. Figs. 2 and 3 are face views 25 of the colter-adjusting plates or members.

Like reference characters indicate corresponding parts throughout the several views.

The reference numeral 12 denotes the mold board provided with the curved shoe 13 and with the curved wing 14 which is 30 a follower for the point of the shoe 13 and which enlarges the path of that shoe throwing the soil a considerable distance to one side and making a good wide regular furrow thoroughly tearing loose and breaking up 35 the plowed earth. In advance of the mold board the colter 15 is disposed which starts the furrow and saves the mold board from contact with stones that otherwise might be encountered in the work. To the plow beam 40 a pair of adjustable apertured plates 16 and 17 are secured, the latter being next to the plow beam and the former being disposed upon and adjustable upon the latter through the medium of its locking pins 18, 18 adapt-

ed to engage the apertured portions 19 of 45 the plate 17. The plate 16 is formed with oppositely disposed elongated slots 20, 20 and the plate 17 is formed with oppositely disposed apertures 21, 21 normally disposed in alinement with the said elongated slots. 50 22 is a strap secured to the plate 16 through the medium of pins 23, 23 which pass through the slots 20 in that plate and through the apertures 21 in the plate 17 and between said strap and plate 16 the colter 15 55 is disposed and secured in adjusted position through the medium of wedges 24, 24. The colter may be adjusted vertically by removing the wedges and manually raising or lowering said colter and then replacing the 60 wedges; it may be moved backward or forward by readjusting the plate 16 upon the plate 17.

What is claimed is:—

A device of the type described, including 65 a colter, adjustably connected members applied to a plow-beam, one of said members having adjusting arcuate slots and perforations, the other of said members having studs engaging said perforations, and aper- 70 tures in alinement with said arcuate slots, a keeper strap applied to receive a colter therebetween and the other of said adjustably connected members, bolts inserted through said keeper strap and said slots and 75 apertures of said adjustably connected members, and wedging members inserted intermediate said bolts and the colter and the outer adjustable member and said keeper strap. 80

In testimony that I claim the foregoing as my own I have hereto affixed my signature in the presence of two subscribing witnesses.

STEVE SIFTER.

Witnesses:

STEVE DROTAR,
SIMON MARORIAN.
